(57) **CLAIM**

The ornamental design for the automatic canning appliance, as shown and described.

DESCRIPTION

FIG. 1 is a top right perspective view of the automatic canning appliance;

FIG. 2 is a front view thereof;

FIG. 3 is a right side view thereof;

FIG. 4 is a rear view thereof;

FIG. 5 is a left side view thereof; and,

FIG. 6 is a top view thereof.

The broken lines shown in the figures represent portions of the automatic canning appliance that form no part of the claimed design.
